UNITED STATES PATENT OFFICE.

WHITFIELD E. JONES, JR., OF SHARPSBURG, PENNSYLVANIA, ASSIGNEE TO PITTSBURGH CAN COMPANY, OF SHARPSBURG, PENNSYLVANIA, A CORPORATION OF PENNSYLVANIA.

CAN.

1,276,660.

Specification of Letters Patent. Patented Aug. 20, 1918.

Application filed November 23, 1917. Serial No. 203,529.

To all whom it may concern:

Be it known that I, WHITFIELD E. JONES, Jr., a citizen of the United States, and a resident of Sharpsburg, in the county of Allegheny and State of Pennsylvania, have invented a new and useful Improvement in Cans; and I do hereby declare the following to be a full, clear, and exact description thereof.

10 My invention relates to improvements in the construction of sheet metal kegs or vessels for holding and in shipment of paints or other heavy liquids, and more particularly to means for strengthening the upper edge 15 of such vessels, and to a novel form of bail-ear and supporting body therefor.

This invention consists of a sheet metal keg or bucket having an open mouth at its upper end adapted to receive an inside tight- 20 fitting friction cover, the upper edge of such keg being provided with an outwardly curled or wired portion adapted to receive the body or securing portions of a bail-ear at opposite sides; such body portions of the 25 bail-ear extending a considerable distance within such curled or wired portion and adapted to strengthen the same.

One of the principal objects of my invention is to provide a bail-ear which may be 30 secured by the wired or outwardly curled edge of the vessel without necessitating the cutting away of any portion of such roll or of the cover lid, thus forming a leak-proof vessel which has not been possible with the 35 class of bail-ears heretofore used.

A further object is to provide a bail-ear of this class which will be stronger and more durable than those heretofore constructed.

While I have shown and described one 40 particular form of vessel and bail-ear in this application, it will be understood that the constructions shown and described are only illustrative of my invention, and may be changed in design and construction within 45 the scope of the appended claim without departing from the spirit of my invention.

In the drawings:

Figure 1 is a perspective view of a complete keg and closure having my invention 50 applied thereto;

Fig. 2 is a similar view of a body portion

of a keg showing my improved bail-ear, the upper edge of said keg being broken away to show the spaced relation of such ears;

Fig. 3 is a perspective view of the bail-ears, in their relative position, separated from the keg; and

Figs. 4, 5, and 6 are enlarged detail views showing the application of my improved bail-ear and the method of supporting and holding the same within the upper portion of the keg.

The numeral 2 designates the body portion of my keg or vessel having an open top. The portion 2 has its upper edge wired or curled outwardly upon itself forming a hollow surrounding or tubular portion 3. Bail-ear members B are adapted to have their body portions 4 secured within the portion 3 of the keg and to have their shank portions 5 extend downwardly therefrom and fit closely against the sides of the vessel 2. These shanks 5 are parallel to each other against such vessel sides, and terminate in ears or loops 6, which are substantially circular in form and extend outwardly from the body portion 2 a substantial distance, so as to allow clearance past the portion 3 to permit of ready attachment and use of a handle member 7.

The body portion 4 of the bail-ears B is semi-circular in form and of such size as to extend partially around the upper portion of the keg body 2, thus facilitating the application of the same in place on said body.

The cover or closure member 8 is adapted to fit within the body portion 2 and is substantially dish-shape. The edge of the closure member 8 is bent downwardly upon itself forming a curved portion C, having an upwardly opening grooved inside friction face adapted to snugly engage the inside surface of the body of the keg, and an outer friction face adapted to engage the portion 3. The outer edge of the groove C has lugs 9 formed thereon at spaced intervals, which are adapted to be bent under the portion 3 when the keg has been filled, and thus firmly lock the cover in place.

It will be readily apparent that by the use of my bail-ear members B it will not be

necessary to slot the body portion 2 on the tubular or wired portion 3, as is now the case when using bail-ears of this general type. The shank portion 5 of my bail ear 5 is of such size that the portion 3 may readily be bent or pressed, as may be desired, around such shank as at 10, and thus serve to support the same. It will also be noticed that it is not necessary to form a recess in 10 the cover member to fit around the bail-ears, as was formerly required when bail-ears of the ordinary construction are used, and thus assist in preventing leakage.

It will also be noticed that with the use 15 of my improved bail-ear the strain or lift is supported by the shank portion 5, as it takes a pull on a straight portion of metal; while in the present form of bail-ears the strain of the lift must necessarily be directly at the junction of the loop and body 20 portion of bail-ear, where there is no shank portion, and the metal from which the bail-ear is formed is greatly weakened at this junction point by the twisting necessary to 25 form the loop. It will thus be apparent that the use of my bail ear provides a much

stronger and satisfactory construction, and the can is much neater in appearance.

Having thus described my invention, what I claim is:—

The combination with a keg having its upper edge turned outwardly and downwardly forming a continuous tubular rim portion, of bail ear members secured in said tubular rim of said keg, each of said bail ear members comprising a body portion semi-cylindrical in form, and a downwardly extending shank portion terminating in a loop, said shank portion being on a line with the plane of the side face of said keg, said shank and loop portions being held in close engagement with the side face of said keg by forcing said tubular rim of said keg around said shank, substantially as described.

In testimony whereof I, the said WHITFIELD E. JONES, Jr., have hereunto set my hand.

WHITFIELD E. JONES, Jr.
